SHIRO ARAKAWA, OF SEATTLE, WASHINGTON.

LUNCH-BOX.

1,183,791.

Specification of Letters Patent. Patented May 16, 1916.

Application filed May 18, 1915. Serial No. 29,002.

To all whom it may concern:

Be it known that I, SHIRO ARAKAWA, a subject of the Emperor of Japan, residing at Seattle, in the county of King and State of Washington, have invented certain new and useful Improvements in Lunch-Boxes; and I do hereby declare the following to be a full, clear, and exact description of the invention, such as will enable others skilled 10 in the art to which it appertains to make and use the same.

This invention relates to boxes, and more especially to those which are adapted to be folded into small compass; and the object 15 of the invention is to produce a folding or knock-down lunch box which when opened or set up will contain sufficient food and drink for the average lunch, but which when folded or closed may be put into the pocket. 20 This object is carried out by constructing the box in a peculiar manner as more fully described and claimed below and as shown in the drawings wherein:

Figure 1 is a perspective view of this 25 lunch box set up ready for use; Fig. 2 is a perspective view of the drinking cup, partly broken away, Fig. 3 is a central longitudinal section through Fig. 1. Fig. 4 is an end elevation of Fig. 1, and Fig. 5 is an end view 30 of the box in its folded condition.

While this device may be of any suitable size and material, I would prefer to make it of metal such as light tin japanned or otherwise treated to prevent rust, with its corners rounded so that it may slip into and out of the pocket with ease; but I do not wish to be limited in this respect, nor as to the use of the device as it is quite obvious that if made on a larger scale it would be 40 serviceable for shipping goods and could be returned by the consignee to the shipper in folded condition. I will describe the invention, however, as applied to a lunch box, and when so used it will have a compartment to contain coffee or other beverage.

Referring to the drawings, the numeral 1 designates the base which is a flat bottom upturned around its sides for a short distance, 2, 2 are the two side panels, 3, 3 are 50 the two end panels, and 13 designates the cover which consists of a flat top plate down-turned around its sides as shown and containing an inner plate 13' whereby a reservoir for liquid is produced within the cover. 55 Through the top plate is an opening surrounded by a threaded nipple 14 through

which this reservoir can be filled when empty. In Fig. 2 is shown a telescopic drinking cup 15 whose lower section is shouldered at 15^b and threaded at 15^a beneath the shoulder so that it may screw into the nipple 14 and close the same, the other sections telescoping at this time around the lower section as seen in Fig. 1. The upper section may carry a cover 15^c hinged at one 60 side thereto and held closed by a latch 15^d at its other side. As above suggested, this reservoir and the nipple and its closure may be omitted if the device is not used as a lunch box.

The upper edges of the sides of the base and the lower edges of the side panels have inter-engaging knuckles 18 through which passes a rod 11 serving as a pintle for the hinge connection thus produced, and at certain points tongues or stops 12 depend rigidly from the knuckles of the panel to rest against the side plate and hold the panel upright as seen in Fig. 1. In similar manner the end panels 3 are hinged at 16 to the 70 end plates of the base, but each panel is fast on its pintle rod 7 whereas the rod is journaled in the knuckles 16 of the end plates. When the end panels stand upright, they are held from falling out by inturned lips 2' at 75 the extremities of the side panels 2, but when the end panels are turned inward and downward as seen in Fig. 5, the side panels may then fall inward and downward onto them. At this time the thickness of the box 80 is only a trifle greater than the thickness of the base and the cover, and the lower edges of the side plates of the latter carry flanges 19 which pass over and inclose all hinge lines at this time.

Throughout the length of the base extends a shaft 6 having beveled gears 4 on its extremities, and at the mid-length of the rods 7 are other beveled gears 5 meshing with them. Rising rigidly from the 85 shaft just inside each of its gears and along the end of the box, is a lever 8; and the parts are so proportioned that when this lever stands upright as seen in Fig. 1 the end panels 3 are upright, whereas when the 90 lever is turned down as seen in Fig. 5 the inter-meshing gears cause the end panels to turn down so as to permit the side panels to fall inward onto them. The bail or handle 8' is of inverted U-shape, its arms passing down by the ends of the cover and being pivoted at 9 to the upper ends of the levers,

and on the cover-ends are latches 10 having spring tips 10.

With the device set up as seen in Fig. 1, when the handle is drawn toward the front 5 and released from the spring tips 10', and then pushed bodily to the rear, the pivot points 9 swing around the shaft 6 and the levers are depressed to the position shown in Fig. 5. When the center of the handle 10 rests on the top of the cover, its ends may be reengaged under the latches, and the box will now stand closed. To open or set up the box a reversal of this operation is necessary. Raising the handle of course raises 15 the levers, and this movement through the inter-meshing gears turns the end panels around their hinge lines 16. As they rise they swing the side panels 2 around their hinge lines 18 until they are upright and 20 are held in that position by the stops 12, and by this time the lips 2' come into position at the corners of the box to limit the outward movement of the end panels. The entire cover may now be bodily raised by 25 sliding the latches upward along the ends of the handle, and the lunch placed inside, after which the cover is dropped into place and its flange 19 holds it there. The reservoir may be filled by unscrewing the drinking cup, and when the latter is replaced it 30 acts as a closure for the nipple 14.

What I claim is:

1. A knock-down lunch box comprising a cover having down-turned sides and an outstanding flange along their lower edges, a base, side and end panels hinged respectively to the sides and ends of the base, inturned lips at the extremities of the side panels, a handle pivoted to the base, and 35 sliding connections between it and the end panels for raising the latter against said lips as the handle is raised and folding the end panels as the handle is depressed.

2. A knock-down box comprising a base, 45 side and end panels hinged respectively to the sides and ends of the base, a swinging handle pivoted in the base, intermeshing gears fixed on the handle and on the hinges of the end panels whereby the latter are raised as the shaft is raised, and means for 50 limiting the upward movements of all panels.

3. A knock-down lunch box comprising a base, a cover, side and end panels hinged 55 respectively to the sides and ends of the base, a shaft journaled through the base, a swinging handle rigid with the shaft, intermeshing gears on the shaft and on the hinges

of the end panels whereby the latter are raised as the shaft is raised, and means for 60 limiting the upward movements of all panels.

4. A knock-down box comprising a base, side and end panels hinged respectively to the sides and ends of the base, a shaft journaled through the base, a swinging handle rigid with the shaft, inter-meshing gears on the shaft and on the hinges of the end panels whereby the latter are raised as the shaft is raised, inturned lips at the extremities of the side panels for limiting the upward movement of the end panels, and stops on the side panels contacting with the base when they are raised for limiting their upward movement.

5. In a knock-down box, the combination with a base having upturned side plates around it, a cover consisting of a top plate and down-turned sides, two side panels hinged at their lower ends to the side plates 80 of the base, and two end panels having rods along their lower ends hinged to the end plates of the base; of beveled gears fast on said rods, a shaft journaled through the end plates of the base, beveled gears thereon 85 meshing with those first named, levers rising rigidly from the shaft near its gears, a handle of inverted U-shape whose arms pass by the ends of the cover and are pivoted to said levers, and means on said cover for engaging said arms.

6. In a knock-down box, the combination with a base having upturned side plates around it, a cover consisting of a top plate and down-turned sides, two side panels 95 hinged at their lower ends to the side plates of the base, and two end panels having rods along their lower ends hinged to the end plates of the base; of beveled gears fast on said rods, a shaft journaled through the 100 end plates of the base, beveled gears thereon meshing with those first named, levers rising rigidly from the shaft near its gears, a handle having upright arms pivoted to the upper ends of said levers, and on each 105 end plate of the cover a spring latch having one end secured thereto and its tip free to detachably engage one of the arms of the handle.

In testimony whereof I affix my signature in presence of two witnesses.

SHIRO ARAKAWA.
